TREATMENT OF HYDROCARBON OILS

Victor Stapleton, Port Arthur, Tex., assignor to
The Texas Company, New York, N. Y., a corporation of Delaware

Application November 15, 1933, Serial No. 698,132

1 Claim. (Cl. 196—58)

This invention relates to the treatment of hydrocarbon oils and has special reference to the cracking of hydrocarbon oils in which a clean condensate stock is subjected to vapor phase cracking treatment and a less clean stock such as reduced crude or a dirty gas oil is subjected to liquid phase cracking treatment.

One of the primary objects of the invention is to more effectively utilize the contained heat of the products resulting from the vapor phase cracking treatment for carrying out the liquid phase cracking treatment.

A further object of the invention is to provide a method involving a combined vapor phase and liquid phase cracking treatment in which only clean condensate stock is subjected to high temperature conditions within a tubular heating coil and in which the clean condensate stock is heated to a temperature sufficient to carry out, not only the vapor phase cracking of the products within the coil, but also the liquid phase cracking of other hydrocarbons which are not passed through the tubular heating coil.

Other objects of the invention will be apparent from the more detailed description.

For a clearer understanding of the invention reference is now made to the accompanying drawing which is a schematic illustration of a type of apparatus suitable for carrying out the invention.

In the drawing the numeral 10 designates a furnace setting having a heating coil 11 mounted therein. The apparatus further includes a reaction and separating chamber 12, a liquid phase cracking and scrubbing chamber 13, a fractionating chamber 14 and other adjunctive elements forming a part of conventional oil cracking apparatus such as a reflux exchanger 15, gasoline condenser 16, accumulator tank 17 for receiving the gasoline fraction, transfer lines for liquid and vapor products et cetera.

In accordance with the invention the oil to be treated, such as, for example, reduced crude or a dirty gas oil, is introduced into the system through line 18 provided with a pump 19 for maintaining the oil under suitable head of pressure.

If desired the fresh oil may be passed through a coil 20 in the reflux exchanger 15 and utilized for cooling the vapors issuing from the fractionating chamber 14 or the coil 20 may be by-passed by a line 21 provided with valve 22 and the fresh oil conducted through line 23 into the upper zone of the liquid phase cracking chamber 13.

If desired, particularly in cases where a high

boiling charging stock such as reduced crude is used, a portion of the charging oil from line 23 may be introduced into the bottom portion of the reaction and separating chamber 12 to flush out the bottom of the chamber and prevent the deposition of coke therein. It has been found to be particularly advantageous to introduce a small amount of an extremely high boiling point oil into chamber 12 adjacent the outlet line 32 to maintain conditions of liquidity in the immediate proximity of the outlet. In most instances it is desirable to introduce the larger proportion of the oil into the upper zone of the liquid phase cracking chamber 13 and to periodically introduce a portion of this oil into the bottom of the digestion chamber 12. In some instances, particularly when rather low boiling hydrocarbons are being utilized as charging stock it may be desirable to continuously or periodically introduce a high boiling residual oil into the bottom of chamber 12 from an extraneous source through line 35 in order to maintain the desired liquid conditions adjacent the outlet.

It may also be desired to introduce fresh charging oil into the vapor transfer line 31 for quenching hot vapor products from the heating coil 11.

The fresh oil introduced into the upper portion of digestion chamber 13 is caused to cascade over a plurality of baffle plates 25 located in the upper portion of the chamber 13 in a downward direction counter-current to the flow of hot vaporous products from the vapor phase digestion chamber 12. The fresh oil coming in contact with the hot vapors is heated to a temperature sufficient to effect conversion of heavier hydrocarbons into lighter hydrocarbons. A considerable volume of liquid is maintained within the chamber 13 so as to allow a digestion period to effect the desired conversion. Lighter constituents, including gas oil which may be contained within the original charging stock, are vaporized within the chamber 13.

Uncondensed vapors, formed in chamber 13 as a result of the conversion treatment and the stripping of the original oil, together with the uncondensed vapor products from the vapor phase digestion chamber 12 are scrubbed by the fresh oil introduced into the upper portion of the chamber 13 and the clean vapors are removed from the chamber through the line 26 and introduced into the bottom portion of the fractionating chamber 14.

The chamber 14 is provided with suitable fractionating elements 27 which cool and fractionate the vapors. The uncondensed vapors from

chamber 14 are passed through the reflux exchanger 15 wherein the vapors are subjected to a further cooling after which they are passed through line 28 to condenser 16 in which the 5 desired gasoline fraction is condensed. The gasoline fraction having the desired end point is thereafter collected in the accumulator tank 17.

The condensate formed in the fractionating chamber 14 is withdrawn from the bottom there- 10 of through line 29 provided with a hot oil pump 30 by which the condensate is forced through the tubular heating coil 11. The oil passing through the heating coil 11 is brought to a temperature sufficient to effect rapid conversion of the hy- 15 drocarbons. For example, the conditions main- tained within the cracking coil may be such as to effect from 15-25% conversion per pass. The hot vapor products are removed from the heating coil 11 through line 31 and introduced into 20 the upper portion of the reaction and separating chamber 12.

The heavier liquid products resulting from the conversion and digestion are removed from the chamber 12 through line 32 at a rate sufficient 25 to prevent any substantial accumulation of liquid within the chamber. The residual liquids withdrawn from chambers 12 and 13 are preferably passed to suitable tar stripping apparatus (not shown) for removing lighter constituents there- 30 from.

While only one reaction and separating chamber has been shown for purposes of illustration, it is understood that any suitable number may be provided, arranged either in parallel or in 35 series, in which cases the liquid is withdrawn from the bottom of each of the chambers at a rate sufficient to prevent substantial accumulation of liquid therein and the withdrawn liquid is passed to the tar stripping equipment as 40 hereinbefore pointed out.

The vaporous products, after being digested in the chamber 12 for a desired period are introduced into a body of hydrocarbon oil in the liquid phase cracking chamber 13 through trans- 45 fer line 33 provided with a reducing valve 34. The pressure within the liquid phase cracking chamber 13 may be maintained lower than that existing in chamber 12. As an example, chamber 12 may be maintained at a pressure rang- 50 ing from 300-500 pounds a square inch and the chamber 13 maintained at a pressure ranging from 150 to 200 pounds per square inch. It is understood that this example is merely for purposes of illustration and that other suitable pres- 55 sure conditions may be maintained as desired.

The hot vapor products introduced into the chamber 13 serve to maintain the body of oil contained therein, at a cracking temperature so as to convert heavier hydrocarbons contained in 60 the charging oil into lighter hydrocarbons as well as to strip the lighter constituents from the fresh charge.

As an example of the temperature conditions which are suitable for carrying out the invention the fresh oil may be heated in the pre- 65 heater 15 to a temperature approximately 500° F. after which it is introduced into the crack-

ing chamber 13 where it is raised to a tempera- 5 ture ranging from 750-850° F. by the hot vapor products from the reaction chamber 12. The condensate, in passing through the heating coil 11, may be brought to a temperature ranging from 900-1000° F. and the cracking chamber 12 maintained at a temperature above 850° F. and preferably of the order of 875° F.-950° F. It will be clear, however, that the temperature condi- 10 tions will depend upon a number of factors and may vary within quite wide limits without in any way modifying or changing the invention.

As hereinbefore mentioned, the hot vapor products in chamber 13 are subjected to a scrub- 15 bing by the fresh oil being introduced into the upper portion of the chamber 13 so that all entrained coke and heavy residual matter may be removed from the vapors before being passed into the fractionating chamber and consequently a clean condensate is produced in the cham- 20 ber 14.

While the preferred embodiment has been de- 25 scribed for purposes of illustration it is under- 30 stood that the invention embraces such other modifications and variations as come within the scope and spirit thereof, and the invention is not to be limited except as necessary to dis- 35 tinguish from prior art.

What I claim is:

In the conversion of higher boiling hydrocar- 30 bon oils into lower boiling ones, the process that 35 comprises heating a confined stream of condensate oil to a cracking temperature of upwards of 900° F. to effect a high rate of cracking per pass, directing the stream of cracked products 40 into an enlarged cracking chamber wherein separa- 45 tion of vapors from liquid takes place, main- 50 taining a cracking temperature of upwards of 850° F., under superatmospheric pressure in the 55 enlarged cracking chamber, separately with- 60 drawing liquid from the enlarged cracking cham- 65 ber at a rate adequate to prevent the accumula- 70 tion of liquid therein, passing the separated 75 vapors without further heating directly into a 80 second cracking chamber below the liquid level 85 therein, introducing fresh charging stock for the 90 process into the system, directing the greater 95 part thereof into a dephlegmating zone in the 100 second cracking chamber above the liquid level 105 therein whereby the stock thus introduced flows 110 countercurrent to the rising vapors separated 115 therein and dephlegmates the separated vapors 120 before reaching the body of liquid oil, main- 125 taining a large body of liquid oil therein at a 130 cracking temperature of a lower order than that 135 of the first cracking chamber by substantially 140 only the heat derived from the vapors, passing 145 the minor part of the fresh charging stock into 150 said enlarged cracking chamber in proximity to 155 the point of withdrawal of liquid therefrom to 160 prevent substantial coking at said point, re- 165 moving the dephlegmated vapors from the de- 170 phlegmating zone of the second cracking cham- 175 ber and subjecting them to fractionation to sepa- 180 rate out a condensate and conducting said con- 185 densate to aforesaid confined stream.

VICTOR STAPLETON.
